UNITED STATES PATENT OFFICE.

JOSEF GROHS, OF WIEN, AUSTRIA.

FIXATION DEVICE FOR RAILS WITH REMOVABLE HEADS.

Application filed June 27, 1927, Serial No. 201,898, and in Austria July 2, 1926.

This invention relates to a device for fixing the removable rail head on rails with gutter-shaped top portion. The commonly used fixation means consist either of screws which are screwed in perpendicularly to the web of the rail through the head and the upper portion of the rail, or of wedge-shaped or flat irons through which the head is clamped on the top portion of the rail.

10 The first kind of fixation requires much time when the rails are laid in the ground. The latter kind of fixation is too expensive, and the removing of the wedge-shaped or flat irons is rather difficult.

15 According to the invention the rails are secured against shifting in longitudinal direction by means of simple bolts which are fixed partly in the head and partly in the top portion of the rail.

20 An embodiment of the invention is shown, by way of example, in the accompanying drawing, in which:—

Fig. 1 shows the fixation for an interchangeable rail head on one side of the rail.

25 Fig. 2 shows the fixation of a rail-head with two running surfaces.

The foot 1 and web 2 of the rail carry a U-shaped top portion 3. The interchangeable

head 5 is situated in the top portion 2 and it is fixed by well fitting fixation bolts 4 engaging with the corresponding grooves in the head 5 and in the top portion 3. When the head 5 has to be removed, the fixation bolts are forced out of the head and the rail in downward direction with the aid of a suitable tool, punch or drift hammer. Fig. 2 illustrates a double-sided head 7 which is embedded in the top portion of the rail 3. Screws 9 serve for securing the bolts 4 in their position.

40 I claim:—

Fixation device for rails with interchangeable head, comprising in combination with the rail head having grooves, a rail consisting of a foot a web and a top portion and having grooves in said top portion alining with the above mentioned grooves, fixation bolts driven into said grooves of the rail head and the top portion of the rail and designed to be forced out in downward direction when said rail head has to be removed, and locking screws for securely holding said bolts in their position.

45 50 55 In testimony whereof I affix my signature.

JOSEF GROHS.
